C. L. GOODRUM

TELEPHONE SYSTEM

Filed April 17, 1920

Inventor:

Charles L. Goodrum.

by C. P. Saper At't'y.

UNITED STATES PATENT OFFICE.

CHARLES L. GOODEUM, OF NEW YORK, N. Y., ASSIGNOR TO WESTERN ELECTRIC COMPANY, INCORPORATED, OF NEW YORK, N. Y., A CORPORATION OF NEW YORK.

TELEPHONE SYSTEM.

Application filed April 17, 1920. Serial No. 374,533.

To all whom it may concern:

Be it known that I, CHARLES L. GOODEUM, a citizen of the United States, residing at New York, in the county of New York, 5 State of New York, have invented certain new and useful Improvements in Telephone Systems, of which the following is a full, clear, concise, and exact description.

This invention relates to telephone exchange systems and more especially to systems wherein machine switching devices are employed for establishing talking connections.

The object of this invention is to provide a system in which connections are established in part by switches of the type actuated from a continuously operating source of power and in part by switches of the step-by-step type.

A feature of the invention relates to a system, comprising switches of the power driven type for extending calling lines, step-by-step switches for further extending said lines and a register controlling mechanism for controlling the operation of said power driven switches, in which a control circuit is provided with a relay therein for sending impulses to operate the step-by-step switches, with a continuously operating interrupting device for actuating said relay and means controlled by the register mechanism for determining the extent of operation of said relay.

A further feature relates to the provision of a continuously operating circuit interrupting device arranged to operate the relay in the control circuit for sending impulses to actuate the step-by-step switches, together with means also operated by said device of determining the number of operations of said relay according to the condition of the register controlling mechanism.

Other features contemplated by this invention will become apparent from a consideration of the following description and the appended claims.

The drawing shows a portion of a telephone exchange system in which the features of the present invention are embodied, certain parts being illustrated diagram-

matically and other parts relating more particularly to the invention being given in detail. There is shown a calling subscriber's line terminating in an office equipped with automatic switches of the continuous-motion or power-driven type. Within the broken rectangle in the lower left-hand corner of the drawing, a register controlling mechanism for controlling the selective movements of the power driven switches is 55 diagrammatically represented. There is also shown in the first office, the outgoing end of a trunk line and the associated mechanism for controlling step-by-step switches in a distant office. The distant office is 60 illustrated at the right of the vertical broken line and is equipped with switches of the step-by-step type which serve to further extend the trunk line incoming from the first office to called subscribers' lines. The 65 circuits and operating magnets of the first of these step-by-step switches are shown in detail in the drawing, while a second switch is represented by a set of movable brushes.

The power-driven switches employed in the first office may be of any suitable and well-known type such as shown and described in detail in the patent to Polinkowsky, No. 1,365,269, issued January 11, 1921.

The register controlling mechanism which serves to control the operation of these switches in accordance with the retractive impulse principle may likewise be of the same design as that disclosed in the above 85 patent. Sequence switch 140, used to perform the circuit changing operations in the outgoing end of the interoffice trunk, may be of the same construction as that described in the patent to Reynolds and Baldwin, No. 90 1,127,808, issued February 9, 1915.

The step-by-step switches located in the second office may be of any suitable design, the one illustrated in detail corresponding to the switches described in the patent to 95 Polinkowsky No. 1,464,109, issued August 7, 1923.

In the present exchange system which comprises offices equipped with power-driven switches and offices equipped with 100

switches of the step-by-step character, trunk lines interconnecting these two types of offices are provided to enable the establishment of a connection between two subscribers' lines involving the use of both power-driven switches and step-by-step switches. The subscribers' lines, such as line 100, belonging to the first office may be extended either manually through the agency of an operator or automatically as by the use of line finder switches to the group selector switch diagrammatically shown in the drawing. In the present illustration only the brushes 102, 103, 104, the brush carriage, power magnet 117 and a few other elements of the group selector switch are shown. As above noted this switch may be substantially the same as the one shown in the patent referred to, No. 1,365,269, issued January 11, 1921, and a detail description herein is not necessary to an understanding of this invention.

The calling line 100 having been extended to the first group selector switch including brushes 102, 103, 104, the calling subscriber proceeds to manipulate his impulse dial to send a series of impulses to position the registers of the register controlling mechanism in accordance with the digits of the desired number. In case the first exchange is of the semi-automatic type, employing operators, the operator receives the called line number from the subscriber and records the same on her keyboard which accomplishes the same result of positioning the registers of the controlling mechanism. Two of the controlling registers 115 and 116 are diagrammatically shown in the drawing, it being understood of course that the controlling mechanism will comprise as many registers as is necessary to suit the capacity of the system and serve when positioned to control the selective movement of the automatic switches in the usual manner.

Dependent upon the character of the record registered on the controlling mechanism either by the calling subscriber or by an operator, the first selector switch including brushes 102, 103, 104 is operated to extend the calling line either to other power-driven switches within the same office or in distant offices or to trunk lines outgoing to offices equipped with switches of the step-by-step type. For example, if the calling subscriber, whose line terminates in the first office, desires to communicate with a subscriber whose line also belongs to the first office the character of the record produced on the controlling mechanism is such that the brushes 102, 103, 104 of the first group selector switch are caused to select a set of terminals 118, 119 and 120 representing a trunk leading to a succeeding group selector 121, 122, 123, of the power-driven type. According to the capacity of the office, this succeeding

switch may be operated to select the called line, either directly or through the medium of other switches.

If however, the calling subscriber wishes to converse with a subscriber whose line terminates in a distant office provided with step-by-step switches, the registration set up on the controlling mechanism causes the group selector including brushes 102, 103, 104 to select the terminals 105, 106, 107 representing the outgoing end of a trunk line which leads to such distant office. The register controlling mechanism which has determined the operation of the power-driven selector switch in accordance with the setting of certain of its registers now functions to control the selective operation of the step-by-step switches in accordance with the set positions of the remaining registers. The manner in which the step-by-step switches are directly operated, according to the numerical designations represented on the register controlling mechanism, constitutes the subject matter of the present invention and to obtain a clearer understanding thereof a detailed description of the operation involved will now be given.

Assuming that the subscriber at substation 100 wishes to obtain a connection with a subscriber's line 170 terminating in a distant office provided with step-by-step switches, the subscriber at substation 100 initiates the call by removing his receiver from the switch-hook and his line is extended as explained, either automatically or by the aid of an operator to the first group selector switch. The designation of the called line 170 is next set up on the registers of the controlling mechanism and the circuits of the first group selector switch prepared for operating such switch to select the terminals 105, 106, 107 of an idle trunk outgoing to the called office. During the trunk hunting movement of the group selector, the test brush 104 successively engages the test terminals 107 of trunk lines in the desired group to select an idle one thereof. When test brush 104 encounters the test terminal 107 of an idle trunk line, full battery potential is found thereon. The test relay 108 is therefore energized in the following circuit: battery, through the winding of relay 133, terminal 107, brush 104, left-hand high resistance winding of test relay 108, to ground. Relay 108 energizes by means of its left-hand winding and completes a circuit through its right-hand winding, contact and armature and the winding of relay 109, to ground. The resistance of the right-hand winding of relay 108 and the winding of relay 109 is sufficiently low to reduce the potential on the multiples of test terminal 107 so as to render the selected trunk busy to other switches.

The energization of the second test relay

109 serves to open the circuit of power magnet 117, bringing the brush carriage to rest, and also cause the advance of the controlling sequence switch (not shown) into a position 5 for extending the conductors 110 and 111 of the fundamental circuit, through to the outgoing end of the selected trunk in the manner disclosed in the above-mentioned Patent No. 1,365,269, issued January 11, 1921. The 10 conductors 110 and 111 are extended over brushes 102 and 103 to the trunk circuit by the closure of contacts 162 and 163 which are operated by the controlling sequence switch. The relay 133 individual to the outgoing 15 end of the trunk circuit also operates in series with the test relays 108 and 109. Relay 133 closes a circuit from ground through its left-hand armature and front contact, lower left contact 135 (1) of sequence switch 140, 20 winding of sequence switch magnet 140, to battery and ground. The sequence switch 140 moves from its normal position 1 into position 2. As sequence switch 140 reaches position 1 $\frac{3}{4}$ its contacts 124 and 125 are 25 closed and the fundamental circuit is completed as follows: Battery, through the winding of relay 130, winding of relay 129, lower contact 124 (1 $\frac{3}{4}$ to 2) terminal 105, brush 102, lower contact 162, conductor 110, 30 contact 164, armature and contact of relay 112, winding of the stepping relay 113, conductor 111, upper contact 163, brush 103, terminal 106, lower contact 125, (1 $\frac{3}{4}$ to 2), to ground. Relays 130, 129 and 113 all 35 become energized in the circuit described. Relay 129, at its armature and contact, closes a bridge across the conductors 141 and 142 of the outgoing trunk circuit. The closure of the trunk causes the energization of the 40 line relay 143 at the first step-by-step switch in the distant office. The circuit of relay 143 may be traced from battery, through the right-hand winding of said relay, back contact and inner left-hand armature of relay 45 144, conductor 141, upper right-hand winding of repeating coil 137, armature and contact of relay 129, lower right-hand winding of repeating coil 137, conductor 142, outer left-hand armature and back contact of relay 144, left-hand winding of relay 143 to 50 ground. Relay 143 attracts its armature and closes a circuit from battery, through the winding of the slow to release relay 145, front contact and armature of relay 143, 55 contact and outer right-hand armature of relay 144 to ground. Relay 145 attracts its armature and prepares the stepping circuit for the primary operating magnet 147. 60 As soon after the closure of the fundamental circuit, and the consequent energization, of relay 130, as the continuously operating interrupter 132 advances, a metallic segment into engagement with brush 165, a circuit is closed from battery, through the 65 contact and right-hand armature of relay 130, right-hand winding of relay 131, brush 165, interrupter 132, to ground. Relay 131 operates in this circuit and completes a holding circuit for itself from battery, through the left-hand winding of said relay, contact 70 and left-hand armature thereof, front contact and left-hand armature of relay 130, to ground. As soon after relay 131 has become energized as a metallic segment of interrupter 132 engages brush 166, a circuit is established from battery, through the winding of relay 130, right-hand armature and contact of relay 131, right-hand armature and contact of relay 133, sequence switch contact 134 (2), brush 166, interrupter 132 to 75 ground. It will be observed that the circuit just traced is free from resistances, and leads directly to ground in shunt of the circuit previously traced through the windings of relays 129 and 113 to ground at the lower 80 contact 125. Relay 129 and stepping relay 113 are therefore shunted out and release their armatures. It should be noted that when interrupter 132 first closed on brush 165, a branch circuit was completed to ground in exclusion of the relays 129 and 113. This branch circuit however, contained the right-hand winding of relay 131 which is of sufficiently high resistance to permit enough current to flow through relays 129 85 and 113 to maintain their energization. When, however, the brush 166 is closed on a metallic segment of the interrupter 132, both relays 129 and 113 are completely 90 shunted out and release their armatures. 100 Relay 113 by deenergizing, completes a circuit from its contact and armature, right-hand winding of relay 114, contact and armature of said relay, and thence to the particular one of the controlling registers of the mechanism on which is registered the designation pertaining to the first group selection in the distant office. The closure of this circuit by the stepping relay causes the register to advance one position in the 105 manner fully explained in the above mentioned Patent No. 1,365,269, issued January 11, 1921. At the same time that relay 113 deenergizes, relay 129 at its armature and contact opens the circuit of the line relay 110 143. Relay 143 retracts its armature and completes a circuit from ground, through the outer right-hand armature and contact of relay 144, armature and back contact of relay 143, inner armature and front contact of relay 145, winding of relay 146, winding of the primary stepping magnet 147, to battery and ground. The stepping magnet 147 115 operates to advance the brushes 153, 154 and 155 one step into operative relation with the first group of trunk terminals. At the first primary step of the switch shaft 167, the off-normal contacts 148 and 149 are closed. Therefore, since relay 146 is energized in 120 series with the primary stepping magnet, 130

a circuit is now completed from battery, through the winding of marginal relay 150, off-normal contact 148, conductor 168, front contact and armature of relay 146, contacts 5 and outer armature of relay 145, to ground. Relay 150 becomes energized in this circuit.

The interrupter 132, continuing to rotate, advances an insulating segment into engagement with the brush 166. This removes the 10 short circuit from around relays 129 and 113 permitting them to again energize. Relay 113, by attracting its armature, prepares for the advance of the controlling register a second step. Relay 129, by attracting 15 its armature, closes the trunk circuit, thus causing the energization of relay 143. Relay 143 opens the circuit of the stepping magnet 147 and relay 146. Stepping magnet 147 releases the stepping pawl ready to advance 20 the brush shaft another step when again energized. The circuits of relays 145 and 146 are alternately opened and closed for brief intervals during the intermittent operation of the armature of the line relay 25 143. Relays 145 and 146, however, are made slow to release and therefore do not become deenergized during the short openings of their circuits. When the interrupter 132 engages its next metallic segment with 30 brush 166, relays 129 and 113 are again short circuited and deenergized. Relay 113 causes the register to take another step and relay 129 opens the trunk circuit to permit the deenergization of the line relay 143.

35 Relay 143 in turn closes the stepping circuit for the primary magnet 147, and the brushes of the selector switch are advanced a second step. In this manner, relays 129 and 113 are successively energized and deenergized by the action of the interrupter 132 and the step-by-step selector switch is stepped forward in its primary movement. When the stepping relay 113 at the controlling mechanism has been operated a 40 number of times corresponding to the designation registered, the fundamental circuit is opened in the well-known manner as by the operation of relay 112. As soon, after the opening of the fundamental circuit at 45 the controlling mechanism, as the interrupter 132 engages an insulating segment with brush 166, relay 130 becomes deenergized and opens the holding circuit of relay 131, which latter relay also releases its 50 armatures. Relay 130 completes a circuit from battery through the winding of sequence switch magnet 140, contact 138 (2), back contact and left-hand armature of relay 130 to ground. Sequence switch 140 55 leaves position 2 and advances into position 13.

60 While sequence switch 140 is moving from position 2 into position 123 $\frac{1}{4}$, the fundamental circuit is maintained open and relay 129 is deenergized. The trunk circuit, how-

ever, is closed at contact 136 when sequence switch 140 reaches position 2 $\frac{1}{2}$ and remains closed until said sequence switch leaves position 123 $\frac{1}{4}$. Relay 143 is therefore operated and remains energized for a comparatively 70 long interval. This interval is so taken as to afford the step-by-step selector switch sufficient time to perform the maximum number of steps in its trunk hunting operation. The line relay 143 by remaining energized, 75 opens the circuit of relay 146 for a time long enough to permit such relay to release its armature. Relay 146 opens the original energizing circuit of relay 150 but relay 150 remains energized by a locking circuit 80 from battery, through the winding of said relay, off-normal contact 148, contact and left-hand armature of relay 150, contact and inner armature of the secondary stepping magnet 151, contact and outer armature of relay 145 to ground. With relay 150 energized, 85 the release of relay 146 closes a circuit for the secondary stepping magnet 151 as follows: battery, through the winding of said magnet, right-hand armature and contact of relay 150, back contact and armature of relay 146, contacts and outer armature of relay 145 to ground. Magnet 151 becomes 90 energized and advances the brushes 153, 154 and 155 into engagement with the first set of terminals in the selected group of trunks. Magnet 151, at its inner armature and contact, also opens the holding circuit of relay 150. Relay 150, releasing its armatures, 95 opens the energizing circuit of the stepping magnet 151. Magnet 151 becomes reenergized and releases its armatures preparatory to advancing the brushes through a second step. If the first trunk is busy a ground potential will be present on the test terminal 158 thereof. Relay 150 is therefore energized in a circuit from battery, through the winding of said relay, contact 148, contact and outer armature of magnet 151, back contact and inner right-hand armature of relay 144, brush 155 to ground at test terminal 158. Relay 150 becomes energized and again closes the operating circuit of the stepping magnet 151. Magnet 151 energizes 100 and advances the brushes on to the second set of trunk terminals. Relay 150 is thereby deenergized to open the circuit of the stepping magnet as above described. This procedure continues until the test brush 155 encounters 105 the test terminal 158 of the trunk leading to an idle succeeding switch. No ground being found on terminal 158 of the idle trunk, the following circuit becomes effective for energizing relay 144; battery, through the winding of relay 150, off-normal contact 148, contact and outer armature of magnet 151, 110 winding of relay 144, contact and outer armature of relay 145 to ground. It will be noticed that the circuit just traced was 115 closed at each step of the selector brushes 120 125 130

but owing to the shunt path to ground at busy test terminals 158, relay 144 did not energize. The shunt path no longer existing around relay 144 since the trunk is idle, this relay becomes energized in series with relay 150. The resistance of relay 144 is such, however, that the relay 150 remains deenergized, hence the operating circuit of the secondary stepping magnet is no longer closed and the brushes 153, 154 and 155 are brought to rest in engagement with the selected set of terminals 156, 157 and 158. Relay 144 places a ground potential on the terminals 158 to render the selected trunk busy. The circuit for the application of this potential may be traced from ground through the outer armature and inner contact of relay 145, front contact and inner right-hand armature of relay 144, brush 155 to the terminal 158. Relay 144, at its left-hand armatures, opens the circuit of the line relay of the first selector switch and extends the trunk conductors 141 and 142 by way of brushes 153 and 154 through to the line relay (not shown) of the succeeding switch. After relay 143 has been deenergized an interval, the slow to release relay 145 releases its armatures. Relay 145 at its outer armature, opens the original energizing circuit of relay 144. Relay 144 however, remains energized in a circuit from battery, through the winding of relay 150, contact 148, contact and outer armature of magnet 151, winding of relay 144, front contact and inner right-hand armature of relay 144, brush 155, terminal 158, and thence to ground at the succeeding switch. This substitute ground at the succeeding switch is supplied before relay 145 has had time to release its armatures, as shown and described in the above mentioned patent to Polin-kowsky No. 1,464,109, issued August 7, 1923.

The change-over and trunk-hunting operations of the first step-by-step selector switch in the distant office have taken place during the time that sequence switch 140 is moving from position $2\frac{1}{2}$ to position $12\frac{3}{4}$. Therefore, the line relay of the second step-by-step switch, illustrated by the brushes 159, 160 and 161, is energized due to the closure of sequence switch contact 136. When sequence switch 140 reaches position $12\frac{3}{4}$, the fundamental circuit is again established for controlling the selective movement of the second step-by-step switch in accordance with the designation registered on the controlling mechanism. The fundamental circuit being closed at contacts 124 and 125, relays 130, 129 and 113 are energized in series with each other. Relay 129 immediately closes the bridge across the trunk circuit 141, 142 to maintain the energization of the line relay of the second step-by-step switch before the trunk circuit can be opened at contact 136 as sequence switch 140 passes into position 13. With relay 130 energized, the above traced circuit is closed for the right-hand winding of relay 131 as soon as the interrupter 132 engages a metallic segment with brush 165. Relay 131 energizes and locks up over its left-hand winding to the front contact and left-hand armature of relay 130.

Each time the brush 166 is engaged by a metallic segment of the interrupter 132, relays 129 and 113 are shunted and deenergized to control the selective movement of the second step-by-step switch in accordance with the designation registered at the controlling mechanism. When this switch has taken the proper number of steps, the fundamental circuit is opened at the controlling mechanism and relay 130 is deenergized immediately thereafter. Relay 130 closes a circuit from battery, through the winding of sequence switch magnet 140, contact 138 (13), back contact and left-hand armature of relay 130, to ground. Sequence switch 140 advances from position 13 into position 15. As sequence switch 140 passes from position $13\frac{1}{4}$ to $14\frac{3}{4}$, the contact 136 is closed to maintain the energization of the line relay at the second step-by-step switch. This interval of time is sufficient to allow for the change-over operation at the selector switch.

As sequence switch 140 reaches position $14\frac{3}{4}$, contacts 124 and 125 again close the fundamental circuit to cause the energization of relay 129 prior to the opening of the trunk circuit at contact 136, as sequence switch 140 passes out of position $14\frac{3}{4}$. In position 15 of sequence switch 140, a second series of impulses are transmitted by relay 129 over the trunk circuit to perform the secondary or line selecting operation at the step-by-step switch. The fundamental circuit is then opened at the register controlling mechanism and immediately thereafter relay 130 becomes deenergized and closes the above-traced circuit for advancing sequence switch 140 out of position 15 and into position 16. In position 16, which is the talking position of sequence switch 140, the calling subscriber's line is extended by way of contacts 124 and 125, to the left-hand windings of the repeating coil 137. The talking circuit, including the right-hand windings of the repeating coil 137, outgoing to the distant office is closed at contact 136. In the well-known manner, the controlling sequence switch (not shown) of the power driven selector switch advances its contacts 162 and 163 into the talking position following the completion of the controlling operation by the register mechanism. Talking current is supplied to the calling line as follows: battery, through the left-hand winding of relay 128, contact 126 (16), contact 124 (16), terminal 105, brush 102, upper

contact 162, upper right-hand winding of repeating coil 101 to ground and from the free pole of battery through the lower right-hand winding of repeating coil 101, relay 5 169, lower contact 163, brush 103, terminal 106, contact 125 (16), contact 127 (16), right-hand winding of relay 128 to ground. Talking current is supplied to the called line in the usual manner at the final switch in 10 the distant office.

At the completion of conversation, the calling subscriber, by replacing his receiver on the switchhook, initiates the release of the power-driven switch in the first office. As 15 the brush carriage is driven to normal the test brush 104 disengages terminal 107 and opens the circuit of relay 133. Relay 133 becomes deenergized and completes a circuit from battery, through the winding of sequence switch magnet 140, right-hand contact 135 (2 to 18), back contact and left-hand armature of relay 133, to ground. Sequence switch 140 leaves position 16 and advances into its normal position 1. Sequence switch 140 on leaving position 16, opens the trunk circuit 141, 142 at contact 136, thereby causing the release of the line relay at the last step-by-step switch in the 20 distant office. The release of this relay causes in the well-known manner the restoration of the switch to its normal position. The release of the switch including brushes 159, 160 and 171 removes the ground from test terminal 158. The removal of 25 this ground causes the deenergization of relay 144. Relay 144 closes a circuit from ground, through its outer right-hand armature and contact, armature and back contact of relay 143, free armature and back contact of relay 145, off normal contact 149, winding of release magnet 152, to battery and ground. Magnet 152 operates in the usual way to cause the restoration of the brush shaft of the first selector switch. All 30 apparatus has thus been completely restored to its normal position and is ready to be taken in connection with subsequent calls.

What is claimed is:

1. In a telephone exchange system, a line, 50 an automatic switch arranged to be operated in a continuous movement, step-by-step operated switches, a register controlling mechanism for controlling the operation of said first switch to extend said line to said step-by-step switches, a control circuit, a relay in said circuit under the control of said mechanism for sending impulses to operate said step-by-step switches to further extend said line, a continuously driven interrupting device for operating said relay, and means for determining the extent of 55 operation of said relay.

2. In a telephone exchange system, a line, 60 an automatic switch arranged to be operated in a continuous movement, a step-by-step op-

erated switch, a trunk line, a register controlling mechanism for controlling the operation of said first switch to extend said line over said trunk to the step-by-step switch, a control circuit, a relay in said circuit under the control of said mechanism for opening and closing said trunk to send impulses thereover, means responsive to such impulses for operating said step-by-step switch to further extend said line, a 65 continuously driven interrupting device for operating said relay, and means operated over said control circuit for determining the extent of operation of said relay.

3. In a telephone exchange system, a subscriber's line, an automatic switch arranged to be operated in a continuous movement, a step-by-step operated switch, a register controlling mechanism for controlling said first switch to extend the subscriber's line to said step-by-step switch, a control circuit, a relay in said circuit for sending impulses in accordance with the setting of said mechanism to operate the step-by-step switch for further extending said line, a stepping relay 70 for said mechanism included in said control circuit, and a continuously driven interrupting device for operating both of said relays, the operation of said stepping relay 75 serving to determine the extent of operation of said first relay.

4. In a telephone exchange system, a subscriber's line, an automatic switch arranged to be operated in a continuous movement, a step-by-step operated switch, a register controlling mechanism for controlling said first switch to extend the subscriber's line to said step-by-step switch, a relaying for sending impulses in accordance with the setting of said mechanism to operate said step-by-step switch for further extending said line, an energizing circuit 80 for said relay, means for successively shunting said relay to cause the operation thereof, and means for determining the extent of 85 operation of said relay.

5. In a telephone exchange system, a subscriber's line, an automatic switch arranged to be operated in a continuous movement, a step-by-step operated switch, a register controlling mechanism for controlling said first switch to extend the subscriber's line to said step-by-step switch, a relay under the control of said mechanism for sending impulses to operate said step-by-step switch for further extending said line, an energizing circuit for said relay, an interrupting device for successively shunting said relay to cause the operation thereof, and means for determining the extent of 90 operation of said relay.

6. In a telephone exchange system, a telephone line, an automatic switch arranged to be operated in a continuous movement, a step-by-step operated switch, a register 95

controlling mechanism for controlling said first switch to extend said telephone line to the step-by-step switch, a control circuit, a relay in said circuit for sending impulses to operate the step-by-step switch for further extending said line, a stepping relay for said mechanism included in said control circuit, and means for successively

shunting both of said relays to cause the operation thereof, said stepping relay serving by its operation to determine the extent of operation of said first mentioned relay. ¹⁰

In witness whereof, I hereunto subscribe my name this 16th day of April A. D., 1920.

CHARLES L. GOODRUM.
